UNITED STATES PATENT OFFICE.

AUGUST G. LIEBMANN, OF BUTTE, MONTANA, ASSIGNOR TO VIGNOLES RAIL CHAIR COMPANY, OF NEW YORK, N. Y., A CORPORATION OF DELAWARE.

RAIL-CHAIR FOR ROADWAYS AND STREET-CROSSINGS.

1,126,521.

Specification of Letters Patent.

Patented Jan. 26, 1915.

Application filed August 27, 1913. Serial No. 787,016.

To all whom it may concern:

Be it known that I, AUGUST G. LIEBMANN, citizen of the United States, residing at Butte, in the county of Silverbow and State 5 of Montana, have invented certain new and useful Improvements in Rail-Chairs for Roadways and Street-Crossings, of which the following is a specification.

This invention relates to railway appliances and particularly to rail chairs.

The main object of the present invention is the provision of a rail chair peculiarly designed for use at country roads, street crossings, floors in terminal buildings, and 15 where tracks are laid on streets.

A further object of the invention is to provide a rail chair of the character above described so constructed as to permit realinement of the rail, provide for a flange- 20 way on either side of the rail, and present a surface extending on either side of the rail to permit of hauling trucks, wagons, etc.

A further object is the provision of a very simple construction for this purpose so designed that the rail may be laterally shifted to bring it to gage without the necessity of removing or readjusting the primary fastenings by which the chair is held to the tie.

A further object is to so construct the 30 chair that all stresses to which the rail is subjected will be properly resisted and the rail braced against vertical, horizontal, and tipping thrusts.

A further object of the invention is to 35 provide means whereby the rail may be readily adjusted without the necessity of tearing up the track and surface flooring in order to accomplish this end.

Other objects will appear in the course of 40 the following description.

The invention is illustrated in the accompanying drawings, wherein:

Figure 1 is a perspective view of a rail chair constructed in accordance with my invention, the tie and rail being also illustrated. Fig. 2 is a plan view of the rail chair illustrated in Fig. 1. Fig. 3 is a side elevation of the construction shown in Fig. 1.

50 Referring to these drawings A designates a tie, which may be of any ordinary form

or material, and B designates a rail of standard cross section. Disposed upon the tie A is a base plate 2 which is held to the tie by means of screw spikes 3 of any suitable character. The base plate 2 is formed at opposite ends with upstanding abutments 3'. The inner face 4 of each abutment is vertical but at its upper end is inwardly extended as at 5 so as to form an overhanging lip. The inner face 4 of each abutment is longitudinally inclined as illustrated in dotted lines in Fig. 2, the inner face of one abutment being oppositely inclined to the inner face of the opposite abutment. Each 60 abutment is downwardly and outwardly inclined upon its outer face and is formed with a laterally projecting bracket 6, this bracket being formed with a screw threaded opening 7 for a purpose to be later stated. 70

Disposed upon the upper face of the base plate 2 and between the abutments so as to engage the rail B, are rail braces 8. Each of these rail braces has a downwardly and outwardly inclined inner face and is formed 75 with a basal foot 9 and a head 10, the head engaging beneath the head of the rail while the foot engages upon the base flange of the rail. The body of each rail brace is inclined upon its outer face as at 11 so as to 80 coact with the inclined faces 4 of the abutments and wedge thereagainst. Each rail brace is formed on one end with an outwardly and laterally projecting arm or tongue 12 which extends parallel to the 85 length of the base plate and which is slotted for the passage of a screw threaded pin 13, the slot being designated 14. If desired the rail braces and abutments may have cored concavities to reduce their weight. Each 90 pin 13 is screw-threaded in the adjacent abutment 3', as illustrated clearly in Fig. 2, and mounted upon the pins 13, which really constitute stud bolts, are nuts 15 engaging one on each side of the tongue or extension 95 12. It will be seen now that by loosening one locking nut and screwing up upon the other nut the corresponding rail brace may be shifted longitudinally parallel to the rail and that its wedging face, bearing against 100 the wedging face of the corresponding abutment, will shift the rail laterally. By mov-

ing one of the wedging rail braces in one direction and the opposite rail brace in the opposite direction a lateral adjustment of the rail in either direction may be secured 5 and this lateral adjustment may be as slight as desired. After the rail braces have been adjusted they are locked in their adjusted position by screwing up upon the nuts 15.

It is to be noted that the rail braces engage beneath the head of the rail and upon the base flange of said rail, that the braces cannot rise because of the fact that they extend beneath the overhanging lips of the abutments, and that they cannot move laterally accidentally because they are held by the abutments and are clamped thereon by the bolt or pins 13. It will further be seen that any tipping strain transmitted to the rail will be translated into a downward 20 thrust against the base flange of the rail. It is further to be noted that the top of each abutment is below the level of the rail and that the upper face of each rail brace is curved downwardly and outwardly so as to be below the upper face of the corresponding 25 abutment. A flangeway is thus provided on either side of the rail for a wheel flange, as shown clearly in Fig. 3.

Where rails are laid in streets, at street 30 crossings, on country roads or on floors of terminal buildings, means must be provided to support a wagon wheel on a level with the rail and close thereto so as to permit of easy hauling of trucks and wagons across 35 the rail. For this purpose I provide flangeway members or housings, preferably in the form of longitudinally extending angle 40 irons 16, the vertical flange of each angle iron resting upon the extremity of the base plate and the horizontal flange resting upon and being supported by the corresponding bracket 6 and abutment. These angle irons, it will be understood, extend longitudinally 45 parallel to the rail and are supported at intervals by the rail chairs. The angle irons are held in engagement with the rail chairs by means of screws 17 which extend through the horizontal flanges of the angle irons and into the perforations 7 of the abutment 50 brackets. By removing these screws it is an easy matter to remove the angle irons and thus expose the adjusting mechanism of the chair. These angle irons 16 not only provide a supporting surface on a level with 55 the tread of the rail and relatively near thereto, but they also house the adjusting mechanism of the chair, preventing snow, ice and mud from collecting there around and thus facilitate the ready adjustment of 60 the chair. It will be noted from Fig. 3 that the horizontal flange of each angle iron 16 terminates in line with the inner face of the lip 5 of the corresponding abutment so that ample space is left for a wheel car or engine flange, this space, however, being too

small to permit a baggage truck wheel to enter, and as street vehicles are supposed only to cross railways at regulation crossings, it is obvious that an even surface is provided over the rail.

The bed plate with its upstanding abutments and the rail braces are preferably made of malleable castings but I do not wish to be limited to this, nor do I wish to be limited to the use of this form of rail chair 75 in connection with street crossings, roads, etc.

It will be seen that with the rail chair described, the rail may be adjusted laterally without any change in the primary fastenings 80 3 and that this adjustment may be readily secured. The chair may be cheaply made, is thoroughly effective in actual practice and conforms to the requirements laid down by the Block Signal and Train Control Board of the Interstate Commerce Commission, in that horizontal, vertical and tipping thrusts are resisted and in that the rail may be laterally adjusted without change in the primary fastenings and without lost motion.

Having thus described my invention, what I claim is:

1. A rail chair comprising a base plate having upstanding abutments at opposite 95 ends, said abutments having overhanging lips on their inner faces, rail braces adapted to engage the head and base flange of a rail and having wedging engagement with the abutments and extending beneath the overhanging lips, and means for holding the rail braces in adjusted position.

2. A rail chair comprising a base plate having upstanding abutments at opposite 105 ends, said abutments having longitudinally inclined inner faces and overhanging lips at the upper ends of said inner faces, rail braces adapted to engage the head and base flange of a rail and extending beneath said lips, and adjusting members projecting 110 from the abutments and through said braces.

3. In a rail chair, a base plate having upstanding abutments at its opposite ends, said abutments having longitudinally inclined inner faces, rail braces disposed between the abutments and having longitudinally inclined outer faces confronting the inclined faces of the abutments, each of said rail braces having a lateral extension, 115 screw threaded members projecting from the sides of the abutments and through said extensions of the rail braces, and nuts on the said screw threaded members engaging said extensions.

4. A rail chair comprising a base plate having oppositely disposed abutments, rail braces disposed between the abutments, means for wedging said rail braces laterally against a rail, and a flangeway member 130

mounted upon each end of the base plate and extending over said abutments and resting thereon.

5. A rail chair comprising a base plate having oppositely disposed abutments, rail braces disposed between the abutments, means for wedging said rail braces laterally against a rail, a flangeway member mounted upon each end of the base plate and extending over said abutments and resting thereon, and means for securing the housing members to said abutments.

6. A rail chair comprising a base plate having upstanding abutments at its opposite ends, rail braces disposed between said abutments and extending downwardly and outwardly, the abutments being less in height than a rail, the inner faces of the abutments engaging said rail braces, flangeway members resting upon the upper faces of said abutments and having their upper faces disposed in the same plane as the tread of the rail disposed between said abutments, and means for engaging the flangeway members with said abutments.

7. A rail chair comprising a base plate, upwardly extending abutments, rail braces disposed between the abutments, means for wedging the rail braces laterally into engagement with a rail, an angle iron disposed at each end of the base plate and each having a vertical flange and a horizontal flange, the horizontal flange resting upon the upper face of the corresponding abutment, and a screw passing through each horizontal flange and into the corresponding abutment, the inner edges of the angle irons being spaced from the rail supported between the abutments.

40 8. The combination with a rail and a tie, of a base plate mounted upon the tie and having oppositely disposed upstanding abutments, rail braces disposed one on each side of the rail and engaging said abutments, means for wedging said rail braces laterally and holding them in adjusted position, and angle irons extending parallel to the rail and disposed at each end of the base plate, each of said angle irons having a vertical flange and a horizontal flange, the horizontal flanges resting upon the upper faces of the abutments, and screws passing through the horizontal flanges and into said abutments.

55 9. The combination with a tie and a rail, of a chair comprising a base plate resting upon the tie and beneath the rail, said base plate having oppositely disposed upwardly extending abutments each formed with an overhanging lip upon the upper end of its inner face, the inner faces of the abutments being oppositely inclined with relation to each other, rail braces engaging one on each side of the rail, the outer faces of the rail braces being longitudinally inclined to co-

act with the inner faces of the abutments and the larger end of each rail brace having a slotted lateral extension, a screw threaded adjusting member projecting from each abutment parallel to the rail and passing through said slotted rail brace extension, adjusting nuts mounted on the screw threaded members, brackets projecting from the abutments, angle irons disposed one at each end of the base plate, each angle iron having a horizontal flange extending over and resting upon a corresponding bracket, and screws passing through said horizontal flanges and into said brackets.

10. The combination with a rail, of a base plate adapted to support the rail and provided with an upstanding abutment, means interposed between the abutment and rail for clamping said rail on the base plate, and a member co-acting with the rail and having its inner face spaced from the head of said rail to form an intermediate flangeway.

11. A rail chair including a base plate having upstanding abutments, the inner faces of which are longitudinally inclined, rail braces disposed between the abutments and having longitudinally inclined outer faces coacting with the inclined faces of the abutments, each rail brace having an extension, and means projecting from the abutments and engaging the extensions of the rail braces for adjusting said rail braces laterally with respect to the base plate.

12. A rail chair including a base plate having upstanding abutments, means for permanently securing the base plate to a sub-structure, adjustable rail braces coacting with the abutments, flangeway members supported on the abutments, and means for adjusting the rail braces to shift a rail laterally with respect to the base plate without disturbing the sub-structure or the means for permanently securing the base plate thereto.

13. A rail chair including a base plate having upstanding abutments and provided with a seat adapted to support a rail, means adapted to be interposed between the abutments and the rail for adjusting the rail laterally with respect to its seat, and members disposed at opposite ends of the base plate and having their inner faces spaced from the head of the rail to form an intermediate flangeway, said members forming a housing for the abutments.

14. A rail chair for railways and rail surface crossings including a base plate having upstanding abutments spaced apart to form a seat for a rail, adjusting wedges adapted to be interposed between the abutments and the rail for adjusting the rail laterally with respect to its seat, members detachably secured to the abutments and having their inner faces spaced from the head of the rail to form an intermediate flangeway, and

locking members connecting the adjusting wedges with the abutments whereby the rail may be adjusted without disturbing the base plate or its support.

5 15. The combination with a tie and a rail, of a base plate permanently secured to the tie, means for adjusting the rail laterally with respect to the base plate, and flange-

way members disposed on opposite sides of the rail and co-acting therewith.

10 In testimony whereof I affix my signature in presence of two witnesses.
